UNITED STATES PATENT OFFICE

125,562

DESIGN FOR A SYRINGE THERMOHYDROMETER OR THE LIKE

Leo Edelmann, Chicago, Ill.

Application May 23, 1940, Serial No. 92,550

Term of patent 14 years

To all whom it may concern:

Be it known that I, Leo Edelmann, a citizen of the United States, residing at Chicago, in the county of Cook and State of Illinois, have invented a new, original, and ornamental Design for a Syringe Thermohydrometer or the Like, of which the following is a specification, reference being had to the accompanying drawing, forming part thereof, and in which:

Figure 1 is a perspective view of a syringe thermohydrometer, showing my design.

Fig. 2 is a top end view.

Fig. 3 is a bottom end view.

I claim:

The ornamental design for a syringe thermohydrometer or the like, as shown.

LEO EDELMANN.
